UNITED STATES PATENT OFFICE.

HENRY G. HEITMEYER, OF CINCINNATI, OHIO.

SWITCH-WORKER.

SPECIFICATION forming part of Letters Patent No. 439,506, dated October 28, 1890.

Application filed June 19, 1890. Serial No. 356,158. (No model.)

To all whom it may concern:

Be it known that I, HENRY G. HEITMEYER, of Cincinnati, in the county of Hamilton and State of Ohio, have invented a new and Improved Switch-Worker, of which the following is a full, clear, and exact description.

My invention relates to an improvement in switch-workers, and has for its object to provide a simple and durable device adapted for attachment to railway-cars and similar vehicles, and so constructed that the driver, conductor, or other designated person may, without interfering with his regular duties and with one hand, expeditiously open or close a switch in the path of the vehicle, and wherein, also, as soon as the device is released it will automatically leave the switch and take a position some distance above the track.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is an end view of a car, the platform being in section, illustrating the application of the device. Fig. 2 is a front elevation of the device detached from the car and partially in section, the switch-rod being shown in its elevated position. Fig. 3 is a similar view, the switch-rod being shown as forced downward to open the switch. Fig. 4 is a side elevation, partly in section, the said view also illustrating a portion of the housing of the device. Fig. 5 is a transverse section on line $x-x$ of Fig. 2, looking in the direction of the arrows 1. Fig. 6 is a similar view upon the same line, looking in the opposite direction, as indicated by the arrows 2. Fig. 7 is a transverse section through the hub of the crown-wheel; and Fig. 8 is a side elevation of the shell, illustrating the position of the trip-plate thereon and disclosing the rack of the sliding bar.

The body of the device consists of a shell 10, of greater length than width, which shell 50 may be of any desired cross-sectional contour,

preferably polygonal, and a bar 11, held to slide in the shell, which bar is ordinarily provided with a central bore 13, in which bore a switch-rod 14 is held to slide. The bar 11 is ordinarily made of greater length than the shell and normally extends above the upper portion of the latter, and the switch-rod 14 projects beyond the top of the bar and below the lower extremity of the shell. The switch-rod 14 terminates at its lower extremity in a socket 15, in which socket a tool A, adapted to act directly upon the switch, is inserted. This tool ordinarily consists of a shank 16 and a head 17 at the lower end of the shank, which head is beveled downwardly upon one side, as is best illustrated at a in Fig. 2; but instead of the head 17 being formed as illustrated it may partake of the character of a colter or friction wheel, in which event the wheel is beveled upon each side at the periphery.

The switch-rod 14 is capable of turning in the bore of the bar 11, but is incapable of a vertical movement, the bar and rod being so attached that the rod may turn, but when moved up or down the bar is forced to move with it.

Upon the upper end of the switch-rod 14 a bevel-gear 18 is securely fastened. From the front of the bar 11, above the upper end of the shell, a stud 19 is horizontally projected, and upon the said stud the hub of a crown-wheel 20 is held to revolve. To the upper face of the crown-wheel hub a hand-lever 21 is securely fastened, and the hub between the lever and the crown-wheel is semicircular, disclosing the stud 19, while upon the exposed portion of the stud a pin 22 is attached, whereby the revolution of the crown-wheel is limited, the said wheel being only able to make a partial revolution upon the stud, as is shown in Figs. 4 and 7, the sectional portion of the hub being indicated by the letter a' .

The crown-wheel 20 meshes with a gear 23, held to turn upon a stud 24, projected from one side of the bar 11 near its upper end, and upon the inner face of the gear-wheel a bevel-gear 25 is formed, which bevel-gear meshes with the bevel-gear 18 of the switch-rod. The crown-wheel upon its outer face near the per-

riphery is provided with two pins 26 and 27, the location of which pins is fully illustrated in Figs. 2 and 7.

Upon the front of the shell 10, a slight distance below the upper end thereof, a trip-plate 28 is secured, which plate extends laterally outward from the shell and vertically upward, the vertical member being bifurcated, as shown in Fig. 2.

- 10 From one side of the shell a bracket-plate 29 is laterally projected, and to the front of the shell a second and smaller plate 30 is secured, which latter plate extends parallel and in the same direction as the bracket-plate 29.
- 15 Between the two plates a spindle 31 is journaled, the outer end of which spindle has secured thereto a hand-lever 32. Upon the spindle a mutilated gear-wheel 33 is securely fastened, and the spindle has likewise attached thereto one end of a spring 34, the other end of the spring being attached in any suitable manner to the body-plate of the shell.

The mutilated gear 33 meshes with a rack-surface 35, formed upon one side of the vertically-movable bar 11, and when the lever 32 is manipulated to force the bar 11 downward the spring 34 is wound up, and when the lever 32 is released the spring acts to automatically carry the bar 11 upward and consequently the attached switch-rod; but the spring is not suffered to entirely unwind, as a pin 36 or equivalent device is attached to the upper portion of the mutilated gear at or near the upper last tooth, which pin is forced by the spring to an engagement with a stop-lug 37, formed upon the bracket-plate 29, as shown in Fig. 2.

A device is preferably attached to the end of the car at each side of the door, as shown in Fig. 1, and between the outer wall of the end and the inner wall. The levers extend beyond the outer wall of the car, and slots 38 are formed in the outer wall to admit of the vertical movement of the bar 11.

- 40 In operation, if the switch is to be turned to the right the upper lever 21 is carried in that direction, whereupon through the medium of the gearing at the upper end of the device the inclined surface of the head of the tool A is brought to the position illustrated in Fig. 2, and the crown-wheel is so turned that the striking-pin 26 thereon is held in position to engage with the trip-plate 28 when the switch-rod is carried downward. The head of the switching-tool having been thus located before the switch is reached, when it is desired to manipulate the switch the driver has simply to force the lever 32 over in the direction of one side of the device, as disclosed in Fig. 3, whereupon the bar 11 and the attached switch-rod are carried downward and the head of the switching-tool is forced between the switch and the main track, while at this instant the pin 26 of the crown gear is brought into engagement with the trip-plate 28, and the said crown gear-wheel

is rotated sufficiently to impart a partial revolution to the head of the switching-tool, and thereby throw the switch to the desired position. If the switch is to be thrown to the left, the movement of the lever 21 is simply reversed, but the movement of the lever 32, controlling the downward stroke, is the same. It is evident that as soon as the lever 32 is released the spring 34 will act to carry the switch-rod and its attached tool upward to their normal positions.

Having thus described my invention, I claim as new and desire to secure by Letters Patent—

1. In a device of the character described, the combination, with a bar capable of a vertical movement and a switch-rod held to revolve in the said bar, of a gearing attached to the rod and bar and a lever connected with the gearing, as and for the purpose specified.

2. In a device of the character described, the combination, with a shell, a bar capable of vertical movement in the shell, and a switch-rod capable of a rotary movement in the bar, of a trip-plate attached to the shell, a gear-connection between the sliding bar and rotary rod, and a lever connected with the gear of the sliding bar, as and for the purpose specified.

3. In a device of the character described, the combination, with a shell, a bar held to slide in the shell and having a rack formed on one side and a switch-rod capable of rotary movement in the bar, of a gear-connection between the upper ends of the bar and rod, a spring-controlled pinion adapted for engagement with the rack-surface of the bar, a lever connected with the pinion, and a trip-plate adapted for engagement with the upper gear-connection, as and for the purpose specified.

4. In a device of the character described, the combination, with a shell, a bar held to slide in said shell, provided with a rack upon one face, and a switch-rod held to turn in the bar and provided with a bevel-gear at its upper end, of a crown-wheel journaled upon the bar, a lever connected with the crown-wheel, a gear-connection between the crown-wheel and the bevel-gear of the switch-rod, and a spring-controlled pinion adapted for engagement with the rack of the sliding bar, as and for the purpose specified.

5. In a device of the character described, the combination, with a shell, a rod held to slide in said shell, provided with a rack upon one face, a switch-bar held to turn in the rod, provided at its upper end with an attached bevel-gear, a crown-wheel journaled upon the bar, provided with pins in its upper face, a lever connected with the crown-wheel and a gear-connection between the crown-wheel and the bevel-gear of the switch-rod, of a trip-plate secured to the shell and adapted to engage with the pins of the crown-wheel and a

spring-controlled pinion engaging with the rack-surface of the bar, as and for the purpose specified.

6. In a device of the character described, 5 the combination, with a shell, a rod held to slide in the shell, provided with a rack upon one face, a switch-bar held to turn in the rod, provided at its upper end with an attached bevel-gear, a crown-wheel journaled upon the 10 bar, provided with pins in its upper face, a lever connected with the crown-wheel, and a gear-connection between the crown-wheel and

the bevel-gear of the switch-rod, of a trip-plate secured to the shell and adapted to engage with the pins of the crown-wheel, a 15 spring-controlled pinion engaging with the rack-surface of the bar, and a tool attached to the lower end of the switch-rod, consisting of a shank terminating in a head having a bevel face, as and for the purpose set forth.
